UNITED STATES PATENT OFFICE.

JOHN T. HOPE, OF KANSAS CITY, MISSOURI.

WALL-VALVE FOR PNEUMATIC CLEANING SYSTEMS.

980,418.

Specification of Letters Patent.

Patented Jan. 3, 1911.

Application filed December 22, 1909. Serial No. 534,563.

To all whom it may concern:

Be it known that I, JOHN T. HOPE, a citizen of the United States, residing at Kansas City, in the county of Jackson and State of Missouri, have invented certain new and useful Improvements in Wall-Valves for Pneumatic Cleaning Systems, of which the following is a specification.

This invention relates to wall valves for pneumatic cleaning systems of that type forming a permanent part of a building, and my object is to produce a valve which, under suction, will automatically close and remain closed when the fixture with which it is associated is not in use, and which under the blast system of cleaning can be locked in closed position.

To this end the invention consists in certain novel and peculiar features of construction and organization as hereinafter described and claimed; and in order that it may be fully understood reference is to be had to the accompanying drawing, in which—

Figure 1, is a view showing a part of a building in section and a part of a pneumatic cleaning system embodying my invention, in elevation. Fig. 2, is an enlarged central vertical section of a part of the cleaning apparatus and building. Fig. 3, is a face view of a valve-equipped wall fixture embodying my invention. Fig. 4, is a section on the line IV—IV of Fig. 1. Fig. 5, is a view on a reduced scale, of a slightly modified form of connection between the stand-pipe and the fixture. Fig. 6, is a perspective view of a key for securing the fixture in or removing it from position.

In the said drawing, 1—1 indicate two floors of a building, and 2 a room wall of such building.

3 is a pipe adapted to be connected to any suitable apparatus for creating suction in or a blast of air through the pipe. 4 is a coupling mounted on said pipe and 5 is a stand-pipe connected at its lower end to said coupling and extending, by preference, up through the partition of adjacent rooms of the building if the cleaning system is installed at the time of the erection of the building or up through the closets of the building if such closets are arranged one above the other, and at a suitable distance above each floor the stand pipe is equipped with a coupling 6. If the stand-pipe is arranged between a pair of partition walls

and the studding, the elbows 7 of the couplings 6, will preferably be equipped with short threaded bushings 8 to receive the rearwardly projecting threaded tubes 9 of 60 hollow fixtures 10, set in one of the walls of the partition, the tubes terminating short of the outer faces of the fixtures so as to provide seats for the valves 11 hinged to and within the fixtures above the tubes, the 65 hinge-pins 12, extending through the shanks 13 of the valves and through a pair of lugs 14 secured rigidly to and within the fixtures, and in order that said fixtures may be conveniently secured in position, they are each 70 provided with a pair of lugs 15, for convenient engagement by a key, consisting, by preference, of a handle 16, and a tubular stem 17 of proper size to extend loosely over tubes 9, and provided at its inner end with 75 diametrically opposite notches 18 for engagement with lugs 15.

Where the building is of such character that the stand-pipe can be arranged in superposed closets, the fixtures will be disposed 80 a greater distance from the couplings, and in this case, the latter will be equipped with short pipes 19, provided with reducers 20 at their outer ends for engagement with the tubes of the fixtures.

Ordinarily there will be only a single fixture to a floor, and a flexible tube 21 (shown by dotted lines) equipped with an ordinary cleaning tool (not shown) to be passed over the carpet, floor or other object to be cleaned, 90 will be fitted upon the tube 9, the valve being first opened as indicated by dotted lines Fig. 2, to accommodate said tube. If the fixtures of the other floors of the building are not in service at the same time, their valves 95 are free to close and gravitate downward and seat against the outer ends of the corresponding tubes 9, against which they are held with an air-tight relation by the suction created in the stand-pipe, it being understood that they are free to close as soon as the flexible tubes 21 are withdrawn from tubes 9.

If the blast system is employed, the fixtures not in use will be closed through the 105 instrumentality of the valves and will be locked closed through the medium of pivoted catches 22, mounted on each valve, said catches being turned after the valves are closed until they overlap the inner sides of 110 the lugs 23 projecting inward from the fixtures.

From the above description it will be apparent that I have produced a wall valve for pneumatic cleaning systems embodying the features of advantage enumerated as desirable in the statement of invention and I wish it to be understood that I do not desire to be restricted to the exact details of construction shown and described as obvious modifications will suggest themselves to one skilled in the art.

Having thus described the invention what I claim as new and desire to secure by Letters-Patent, is:

1. The combination in a pneumatic cleaning system, of a stand pipe provided with a coupling, a hollow fixture secured to said coupling and provided with a tube, and a valve carried by and within the fixture and adapted to seat against the outer end of said tube and close the same.

2. The combination in a pneumatic cleaning system, of a stand pipe provided with a coupling, a hollow fixture secured to said coupling and provided with a tube, a valve carried by and within the fixture and adapted to seat against the outer end of said tube and close the same, and means for locking said valve in its closed position.

3. The combination in a pneumatic cleaning system, of a stand pipe provided with a coupling, a hollow fixture secured to said coupling and provided with a tube, a valve carried by and within the fixture and adapted to seat against the outer end of said tube and close the same, a lug projecting from the fixture, and a pivoted catch mounted on the valve and adapted to engage the lug of the fixture and lock the valve in its closed position.

4. The combination in a pneumatic clean-

ing system, of a stand pipe provided with a coupling, a hollow fixture secured to said coupling and provided with a tube, and a hinged valve carried by and within the fixture and adapted to seat against the outer end of said tube and close the same, and when open, leave the tube unobstructed.

5. The combination in a pneumatic cleaning system, of a stand pipe provided with a coupling, a hollow fixture provided with a tube terminating at its outer end short of the face of the fixture and projecting at its opposite end rearwardly beyond the fixture and externally threaded, means for connecting the threaded end of the tube with the coupling, lugs projecting from the fixture to enable it to be readily turned in securing it in or removing it from position, and a valve carried by and within the fixture to seat against the outer end of the tube.

6. The combination in a pneumatic cleaning system, of a stand pipe provided with a coupling, a hollow fixture provided with a tube terminating at its outer end short of the face of the fixture and projecting at its opposite end rearwardly beyond the fixture and externally threaded, means for connecting the threaded end of the tube with the coupling, lugs projecting from the fixture to enable it to be readily turned in securing it in or removing it from position, a valve carried by and within the fixture to seat against the outer end of the tube, and means for locking said valve in its closed position.

In testimony whereof I affix my signature, in the presence of two witnesses.

JOHN T. HOPE.
